COLLAPSIBLE CORE

Jay A. Craven, Dayton, Ohio

Application July 24, 1936, Serial No. 92,413

4 Claims. (Cl. 25—131)

This invention relates to a collapsible core for use in the construction of hollow concrete structures and it is designed more particularly for use in the construction of a hollow concrete wall. In the construction of hollow concrete walls an inner form is arranged between and spaced from the side members of the outer form and inasmuch as it is not usually practical to make this inner form of a length equal to the length of the wall it is customary to use a plurality of collapsible cores or sections which are arranged end to end between the side members of the outer form. The two parts of the hollow wall should have no concrete connection between them but are connected one to the other only by metallic tie bars, there being usually a plurality of series of such tie bars, the bars of each series being arranged one above the other in spaced relation. The adjacent ends of the cores of the inner form abut against the opposite sides of the respective tie bars and this necessarily results in the ends of the cores being spaced short distances one from the other. The cores heretofore used have been of such a character that the soft concrete would enter the space between adjacent cores, above and below the tie bars, and would so fill this space as to form a concrete tie between the two parts of the wall which is highly objectionable because it permits of the transmission of moisture from the outer part of the wall to the inner part thereof.

One object of the present invention is to provide a collapsible core which will be of simple inexpensive construction and can be easily collapsed.

A further object of the invention is to provide such a core which will have no overlapping parts slideable one upon the other.

A further object of the invention is to provide a collapsible core of such a character that the spaces between adjacent cores, above and below the tie bars, will not be filled with concrete, thus avoiding any connection between the two parts of the hollow wall other than the metallic tie bars.

Other objects of the invention may appear as the device is described in detail.

In the accompanying drawing Fig. 1 is a plan view of a collapsible core embodying my invention; Fig. 2 is a side elevation of the same, partly in section; Fig. 3 is an end view of such a core, partly in section; Fig. 4 is a sectional detail view of a portion of the core; Fig. 5 is a horizontal sectional view taken through a concrete wall, showing portions of two cores in position in the wall; Fig. 6 is a vertical section of a portion of a wall which has been formed with my collapsible

cores showing the complete separation of the two parts of the wall; Fig. 7 is a sectional detail view of a portion of such a concrete wall showing the inwardly extending fins formed between the cores; and Fig. 8 is a plan view of the guide for the actuating member.

In the drawing I have illustrated one embodiment of my invention and I have shown the same as comprising parallel side members or walls 10 which are connected at their ends by end members or walls, each of which end members has a part which is movable inwardly with relation to the side members in such a manner as to draw the side members one toward the other and thus collapse the core. In the particular construction shown each end member comprises two longitudinal parts 11 which are pivotally connected one to the other and with the adjacent edges of the respective side members. Preferably each part 11 of the end member is provided with hinge 20 bearings to receive hinge pins 12.

Arranged between the side members 10 is an actuating device which is so connected with the respective end members that it will impart inward or outward movement to said members and thus collapse or expand the core. Preferably this actuating device comprises a longitudinally movable member 13 which is connected with the end members by links 14 each of which is pivotally connected at one end to the actuating member 13 and pivotally connected at its other end to a U-shaped lug 15 which extends about the pivot pin 12 which connects the two parts of the end member one to the other. The links and the actuating member function as a toggle and when the actuating member is moved downwardly the links will extend the end members thus forcing the side members to their outermost positions. If the two links are moved into alignment one with the other the core will be positively locked 40 in its extended position, but it is sometimes desirable to move the end members outwardly slightly beyond their normal extended positions and I have provided means for retaining the core members in their normal extended positions without 45 fully extending the links, as will hereinafter appear. The upward movement of the actuating member will move the connected edges of the two parts of each end wall inwardly, thus drawing the side members inwardly to the positions shown in 50 dotted lines in Fig. 4, thereby simultaneously moving the four core members out of contact with the concrete wall. The actuating member may be manipulated in any suitable manner but I prefer to provide a screw for actuating the same,

and, as here shown, a nut 16 is rigidly secured to a supporting member or plate 17 which is carried by the side members of the core and is slidably connected therewith, as by means of the 5 metallic clips 18, so that the side members may have movement with relation to the supporting member 17. Rotatably mounted in this nut is a screw 19 the lower end of which has swiveled connection with the upper end of the actuating member 13, is shown at 20, so that the screw may rotate with relation to the actuating member but the actuating member will move vertically with the screw. Any suitable means may be provided for rotating the screw and, as here shown, the 10 upper end of the screw is squared to receive a socket wrench or the like. The pitch of the screw thread is sufficiently low to render the screw self-locking so that the core members will be automatically secured in any position to which they may be moved.

If desired telescoping guide members 21 and 22 may be rigidly secured to the inner surfaces of the side members to maintain the same in their proper relative positions and, if desired, the side 25 members may be reinforced, as by means of angle bars 23. It may also be desirable to provide a guide to retain the actuating member 13 in an approximate vertical position and thus cause substantially equal movements to be imparted to the 30 two end members. As here shown overlapping guide plates 32 are secured to the respective side members and provided with registering apertures to receive the actuating member. The apertures are of such size and shape as to prevent any appreciable movement of the actuating member lengthwise of the core, that is, toward either end member, but to permit the guide plates to move with relation to the actuating member in a direction transverse to the core, so as not to interfere 35 with the expansion and contraction of the core members.

In order to prevent the formation of a concrete tie between the two parts of the hollow wall each end member of the core is provided with 40 outwardly extending vertical parts spaced one from the other to form between them a recess. In the present construction the two parts 11 of the end wall are curved outwardly about separate axes extending lengthwise thereof so that the 45 intermediate or connected edges of these parts are spaced inwardly over the outermost surfaces thereof to form a substantially V-shaped recess. When the several cores constituting the inner 50 form are placed in position between the side members of the outer form the adjacent ends of the cores will abut against the opposite sides of tie bars 24, as shown in Fig. 5. These tie bars are supported by the side members of the outer 55 form and extend through and beyond said side members, the end portions of the tie bars being weakened, as shown at 25 in Fig. 6, to permit these end portions to be broken off after the concrete has set. When the two cores are in contact with the tie bar the recesses in the end 60 members of the two cores will be in opposed relation so as to form between them a vertical chamber 26 which is of a width or diameter substantially greater than the thickness of the tie bars. When the soft concrete is poured into the forms 65 it will enter the V-shaped spaces between the outer sides of the two cores but the coarse aggregate will quickly clog the narrow space between the outwardly curved portions of the end members 11 so that little or no concrete will enter 70 the chamber 26 and any small quantity of con-

crete which may enter that chamber will drop to the bottom of the chamber where it will do no harm. Consequently the intermediate space between the outwardly curved portions of the end members, which constitutes the chamber 26, will 5 never be filled with concrete and there will be no concrete tie between the two parts of the concrete wall. The concrete which enters the V-shaped spaces at the sides of the cores will assume the shape shown in Fig. 7 but the fins 27 thus 10 formed will terminate in the narrow spaces between the outwardly projecting curved portions of the end members so that the fins on the two parts of the concrete wall will be spaced a very substantial distance one from the other, as shown 15 in Fig. 6, where the concrete wall is indicated by the reference numeral 28.

The cores may be of any desired dimensions and will usually be made of a depth corresponding to that portion of the wall which can be 20 formed by a single pouring of concrete. This depth will vary and it may be substantially greater than the length of the core. When one section of the wall has been poured and has set the cores are collapsed and moved upwardly in 25 preparation for the pouring of another section of the wall, the lower end of each core remaining in the formed portion of the wall to properly locate the core with relation thereto. To facilitate this resetting of the core the side members 30 may be provided near their lower ends with spurs 38 which will bite into the wall and temporarily support the core in its adjusted position. The side members may, if desired, be provided with means, such as apertured lugs 34, for attaching 35 a lifting device to the core, to facilitate the handling of the same.

While I have shown and described one embodiment of my invention I wish it to be understood that I do not desire to be limited to the details 40 thereof as various modifications may occur to a person skilled in the art.

Having now fully described my invention, what I claim as new and desire to secure by Letters Patent, is:

1. A collapsible core for a concrete structure comprising side members and end members connecting the adjacent edges of said side members, each end member having two longitudinal parts pivotally connected one to the other and to the 50 edges of the respective side members, whereby the inward or outward movement of said end members will impart corresponding movement to said side members, an actuating member arranged between said side members and operatively connected with said end members, and an operating device having supporting connection with both side members and operatively connected with said actuating member to cause the latter to impart either outward or inward movement to said end members, the connection between said operating device and said side members being such as to permit the latter to move toward and from each other.

2. A collapsible core for a concrete structure 65 comprising side members and end members connecting the adjacent edges of said side members, each end member having two longitudinal parts pivotally connected one to the other and to the edges of the respective side members, whereby the 70 inward or outward movement of said end members will impart a corresponding movement to said side members, a vertically movable actuating member arranged between said side members, links pivotally connected with said actuating 75

member and the respective end members, a supporting member mounted on said side members and slidably connected therewith to enable said side members to move toward and from each other, and a screw mounted on said supporting member for vertical movement with relation thereto and operatively connected with said actuating member.

3. A collapsible core for a concrete structure 10 comprising side members and end members connecting the adjacent edges of said side members, each end member having two longitudinal parts pivotally connected one to the other and to the edges of the respective side members, whereby 15 the inward or outward movement of said end members will impart a corresponding movement to said side members, a vertically movable actuating member arranged between said side members, links pivotally connected with said actuating member and the respective end members, an operating device supported on said side walls and 20 operatively connected with said actuating member to impart vertical movement thereto, and a guide for said actuating member arranged between said 25 side members and acting on said actuating mem-

ber to hold the same against substantial transverse movement toward either end member.

4. A collapsible core for a concrete structure comprising side members and end members connecting the adjacent edges of said side members, each end member having two longitudinal parts pivotally connected one to the other and to the edges of the respective side members, whereby the inward or outward movement of said end members will impart a corresponding movement to 10 said side members, a vertically movable actuating member arranged between said side members, links pivotally connected with said actuating member and the respective end members, an operating device supported on said side walls and 15 operatively connected with said actuating member to impart vertical movement thereto, and a guide members carried by and movable with the respective side members and having aligned openings through which said actuating member extends, said openings being shaped to permit said 20 side members to move toward and from said actuating member and to hold the latter against substantial movement toward either end member.
